KNEE GUARD

Daniel Bednarczuk, 37-04 Parsons Blvd., Flushing, N.Y.
11354, and Arnold T. Milton, 7 Olmsted Road, Scars-
dale, N.Y. 10583

Filed June 10, 1971, Ser. No. 152,018

Term of patent 14 years

Int. Cl. D2—02

U.S. Cl. D2—27

FIG.1

FIG.2

FIG.3

FIG.4

FIG.5

FIG.6

FIG.7

FIG.8

FIG. 9

FIG. 1 is a side elevational view of a knee guard showing our new design in relaxed position;

FIG. 2 is a front elevational view thereof;

FIG. 3 is a rear elevational view;

FIG. 4 is a sectional view taken on the line 4—4 of FIG. 1;

FIG. 5 is a longitudinal sectional view taken on line 5—5 of FIG. 2;

FIG. 6 is a side elevational view of another embodiment of our design wherein the outside flaps of the knee guard comprise separate elements which are snapped on to the inner guard member;

FIG. 7 is a front elevational view of the embodiment of our design shown in FIG. 6;

FIG. 8 is a sectional view thereof taken on the line 8—8;

FIG. 9 is a side elevation view of the design as shown in FIG. 1 in a 120° knee bend position.

We claim:

The ornamental design for a knee guard, as shown and described.
